SELF-ACTUATING HOLDER FOR PHONOGRAPH RECORDS

Garry Kieves, 246 Rosalyn Road,
Winnipeg 13, Manitoba, Canada

Filed July 30, 1971, Ser. No. 167,886

Term of patent 14 years

Int. Cl. D6—04

U.S. Cl. D6—185

FIG. 1 is a top plan view of a self-actuating holder for phonograph records embodying my new design.

FIG. 2 is a bottom plan view thereof.

FIG. 3 is a side elevational view.

FIG. 4 is a front elevational view.

FIG. 5 is a rear elevational view.

I claim:

The ornamental design for a self-actuating holder for phonograph records, as shown.
